UNITED STATES PATENT OFFICE.

THOMAS FISHER, OF MADEIRA, OHIO.

RAILWAY-CAR ROUTE REGISTER AND INDICATOR.

1,369,232.

Specification of Letters Patent. Patented Feb. 22, 1921.

Application filed October 22, 1920. Serial No. 418,832.

To all whom it may concern:

Be it known that I, THOMAS FISHER, a citizen of the United States, and residing at Madeira, in the county of Hamilton and 5 State of Ohio, have invented a new and useful Improvement in Railway-Car Route Registers and Indicators, of which the following specification is a full disclosure.

My invention relates to a junction or route 10 indicator as a permanent record system and as a permanent fixture thereof applied to a railway car for indicating and recording junctions or points at which the car is transferred from the lines of one railroad company to the lines of another, the return location 15 and the period such car remains in the possession of the transferee, for which a per diem rental charge is made.

The transfer from one line to another is 20 necessary in transporting shipments to and from various destinations not directly upon the lines of one railroad company. According to railroad practise, a junction card is tacked upon the car, designating the junction 25 for transfer, which is both the delivery and return point, or other data required. The cards are frequently lost, leaving nothing on the car to indicate the place to which the car must be returned, causing delay and 30 expense before authorized return directions are secured.

An object of the invention is to provide a 35 holder or container, as a fixture permanently secured upon a railroad car and at a convenient and accessible place, for journaling a pair of manually rotative spindles, as unwinding and rewinding web supports for a continuous strip of paper or other suitable material, adapted to be fed through apertures in the face wall of the container, or 40 passing display windows or openings of the container for exposing definite strip areas or divisions as consecutive indicator, display or data record spaces.

45 The apertures in the front wall of the casing are arranged and spaced to provide two adjacent platen surfaces with a guide roller journaled in the casing and extended between said platen surfaces so that the web 50 may be fed from one support within the casing through an aperture and over one platen surface, thence inwardly and outwardly around the roll and over the second platen surface, and thence inward through an aperture to a second web support. This exposes 55 two consecutive record or entry spaces of

the web, with the casing and roller as a margin-frame for each web space.

Various other advantages and features of the invention will be more fully set forth 60 in the description of the accompanying drawings, forming a part of this specification, and in such drawings like characters of reference denote corresponding parts throughout the several views, of which— 65

Figure 1 is a front elevation of the device with a portion of the hinged cover plate shown as swung to an open position.

Fig. 2 is a central section through Fig. 1, the cover plate being in the closed position. 70

Referring to the drawings, 1 indicates a box-like container or casing of rigid and durable construction, adapted to be securely fastened to a railway car and capable of 75 withstanding heavy usage and weather conditions to which a car as a freight car is usually subjected.

The casing provides a support for the spindles 2, 3, which are adapted to project through the side walls, and extend exteriorly of one side of the casing for receiving the thumb pieces 4, 5, respectively, for manually rotating the spindle in unwinding the strip 6 from the web, say of spindle 2 and rewinding upon spindle 3. The strip 6 may 80 be of a tenacious grade of paper or cloth, or any other material suitable for the purpose, desirable to withstand rough usage, possessing a satisfactory impervious surface for making permanent record entries. 85 The front wall 7 of the casing is apertured and provided with recessed platen surfaces over which the paper is fed to expose portions of the strip for display and entry purposes. The platen surfaces are formed 90 by cross bars or plates 8, 9, spaced relatively and from the front wall longitudinally to provide the paper receiving apertures 10, 11. Intermediate the bars 8, 9, I provide a guide roller 12 over which the 95 strip loops in passing from the first platen surface to the second. The strip is fed to and from spindle 2 to and through the aperture 10, over the platen surface of bar 8, threading inwardly and outwardly around 100 the roller 12, then over the platen surface of bar 9, and through aperture 11 to the spindle 3.

This construction provides two strip exposure spaces longitudinally of the strip 110 and relatively spaced, each of sufficient area for displaying the required data or for mak-

ing the necessary entries for the contemplated use. The strip can be fed in either direction by rotating a respective spindle. The data preferably is entered upon the exposed strip portion or space over the platen bar 8, after which it is advanced to the second exposed space for display purposes. In this manner the junction point and date of transfer or other instructions are easily ascertained, a permanent record of every entry is always maintained with the car. To protect the exposed portions of the strip, the casing is provided with a hinged cover 13 capable of being swung upwardly inverted in order to permit reading or making an entry upon the strip. The casing has a car identification plate 14 permanently fixed thereon, usually containing a number corresponding to the number of the car, so that the casing with its particular car record cannot be transferred to another car without detection. Transferring cards, under the card system, with the record cards tacked to the car, is frequently resorted to by railroad employees to shift the responsibility, and who, in some cases, maliciously destroy the cards when they have failed to follow orders. The junction card usually is tacked

upon the side of the car, has a limited space for entries and is exposed to the weather which renders the record data illegible, causing error, delay and expense, all of which is avoided with the permanent record strip as a car fixture consecutively presenting the entries upon a continuous strip suitably housed and protected.

Having described my invention, I claim:

An indicating and recording device for railway car junction routing, comprising a casing having a narrow cross member, and two platens adjacent each other separated by said narrow cross member so that successive forms on a web threaded over one platen, under the cross member and over the other platen may be visible at the same time, and a pair of web supports journaled within the casing rotative to withdraw the web from one over said platens and rewind the same upon the other.

In witness whereof, I hereunto subscribe my name, as attested by the two subscribing witnesses.

THOMAS FISHER.
